US00D989145S

(12) **United States Design Patent** (10) **Patent No.:** **US D989,145 S**
(45) **Date of Patent:** **** Jun. 13, 2023**

(54) **DISINFECTION ROBOT**

(71) Applicants: **UBTECH NORTH AMERICA RESEARCH AND DEVELOPMENT CENTER CORP**, Pasadena, CA (US); **UBTECH ROBOTICS CORP LTD**, Shenzhen (CN)

(72) Inventors: **Francisco Jose Hernandez**, Long Beach, CA (US); **ChengKun Zhang**, Temple City, CA (US); **Huan Tan**, Pasadena, CA (US)

(73) Assignees: **UBTECH NORTH AMERICA RESEARCH AND DEVELOPMENT CENTER CORP**, Pasadena, CA (US); **UBTECH ROBOTICS CORP LTD**, Shenzhen (CN)

(**) Term: **15 Years**

(21) Appl. No.: **29/814,351**

(22) Filed: **Nov. 5, 2021**

(51) LOC (14) Cl. **15-99**

(52) U.S. Cl.

USPC **D15/199**

(57) **CLAIM**

The ornamental design for a disinfecting robot, as shown and described.

DESCRIPTION

FIG. 1 is a first perspective of a disinfecting robot showing the claimed design in accordance with the present disclosure;

FIG. 2 is a second perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof; and,

FIG. 9 is a perspective view of the disinfecting robot with an upper part retracted.

The broken lines in the Figures are for the purpose of illustrating portions of the article that form no part of the claimed design.

1 Claim, 9 Drawing Sheets
